United States Patent Office

Des. 201,771
Patented July 27, 1965

201,771

VIEWER UNIT FOR READING DOCUMENTS

John R. Regal, East Brunswick, N.J., assignor to Sperry
Rand Corporation, New York, N.Y., a corporation of
Delaware

Filed Nov. 2, 1964, Ser. No. 82,437

Term of patent 14 years

(Cl. D61—1)

FIG. 1

FIG. 2

FIG. 1 is a front perspective view of a viewer unit for reading documents embodying my new design; and
FIG. 2 is a rear perspective view thereof.

The essential features of the design reside in the portions shown in solid lines on the drawings.

I claim:

The ornamental design for a viewer unit for reading documents, substantially as shown and described.
